UNITED STATES PATENT OFFICE.

FRANK H. SILVERTHORNE, OF NEW YORK, N. Y.

BOTTLE-CLOSURE.

1,390,549.

Specification of Letters Patent. Patented Sept. 13, 1921.

Application filed August 25, 1919. Serial No. 319,783.

To all whom it may concern:

Be it known that I, FRANK H. SILVERTHORNE, a citizen of the United States and resident of New York city, in the county of New York and State of New York, have invented certain new and useful Improvements in Bottle-Closures, of which the following is a specification.

The invention relates in general to a 10 valvular pour out bottle closure of the type which includes a valve seat adapted to be affixed to the bottle and a rotatably mounted valve for closing the bottle and for directing the stream when the contents are poured 15 from the bottle. This invention constitutes a continuation in part of the invention disclosed in my copending application, Serial No. 216,154, filed February 9, 1918, and relates to certain improvements in construction 20 over the device shown in the preceding application.

In the structure shown in the preceding application the ferrule or retaining ring which held the attachment to the bottle engaged an inflexible retaining ring within 25 which the nozzle member was mounted for rotary movement and acted therethrough to hold a cork washer in position between the valve and its seat. In the commercial manufacture of these devices in large quantities 30 difficulty is experienced in obtaining the cork washers of approximately the same thickness. Where the washers are unusually thick and were installed in the previously disclosed device an undesirable amount of 35 friction was introduced between the washer and the valve seat, thus causing the valve to work stiffly and under some conditions preventing the rotation of the same by ordinary manual efforts.

Accordingly, one of the objects of the present disclosure is to design a simple form of means for mounting the valve in rotary position on its valve seat in such a manner 45 as to permit the requisite frictional resistance to free rotary movement of the valve and at the same time permit the use of cork inserts or washers of the commercially varying differences in diameter from the prescribed thickness.

Broadly, this object is attained by substituting a spring ring for the inflexible retaining ring in the prior disclosure, so that the retaining ferrule will hold the spring

ring and the spring ring will in turn bear 55 on the valve to press the same resiliently into engagement through the cork washer with the valve seat.

Incidental to the object of simplifying the construction disclosed in the prior structure, the invention has for a further desideratum, the utilization of this spring ring for the purpose of limiting the rotary movement of the valve to and from its open position and to hold the ring against rotary 65 movement.

This object is attained by pressing a pair of depressions into the spring ring and positioning one of the depressions in an arcuate recess in the valve member and positioning the other depression in a recess formed in the valve seat member.

Various other objects and advantages of the invention will be in part obvious from an inspection of the accompanying drawings 75 and in part will be more fully set forth in the following particular description of one form of mechanism embodying my invention, and the invention also consists in certain new and novel features of construction 80 and combination of parts hereinafter set forth and claimed.

In the accompanying drawings:

Figure 1 is a vertical sectional view taken axially through a preferred embodiment of 85 my invention shown attached to the upper portion of a bottle neck and taken on the line 1-1 of Fig. 2;

Fig. 2 is a plan view looking down upon the device shown in Fig. 1 and with parts 90 broken away to show internal construction;

Fig. 3 is a view in side elevation of a combined valve and nozzle element shown in Fig. 1 and detached from its coördinated parts;

Fig. 4 is a vertical view of the retaining ferrule;

Fig. 5 is a plan view of the valve seat element;

Fig. 6 is a diametrical sectional view of 100 the spring retaining ring taken at right angles to the view shown in Fig. 1 to illustrate the lug forming depression; and

Fig. 7 is a plan view looking down upon the part shown in Fig. 6.

In the following description and in the claims, parts will be identified by specific names for convenience of expression but

they are intended to be as generic in their application to similar parts as the art will permit.

The closure constituting the subject-matter of this invention is designed as an article of manufacture for attachment to any kind of a bottle or other receptacle of suitable size and is arranged to be placed on top of the bottle and fastened thereto by any conventional ferrule fastening device. The upper portion of such a bottle is shown at 10 in Fig. 1, positioned on top of which is a cork ring washer 11 constituting a cushioning device between the attachment and the bottle to prevent breakage when the parts are assembled in a capping machine. The washer is designed to be placed under sufficient pressure to form a tight seal between the attachment and the bottle. A flanged disk 12 hereinafter identified as a nozzle seat is fitted within the ring washer 11 and is provided with an upstanding and outlining rim 13 positioned on top of the washer at its outer edge to form an angled joint with the washer. The top of the nozzle seat within the inclosing rim is flat so as to provide a smooth bearing surface 14. The nozzle seat is provided with a circular liquid outlet opening 15 adjacent one side thereof and with a relatively small air inlet opening 16 positioned diametrically across the surface from the opening 15, as shown in Fig. 5. The underside of the air opening 16 is countersunk to provide a relatively short, wide spreading funnel shaped opening 17 designed to provide a free clearance to the air as it enters the bottle. The portion of the air inlet directly above the funnel shaped opening is of relatively small diameter and constitutes a choked passageway 18 for the air just before it enters the bottle.

Revolutely positioned on the nozzle seat is a nozzle unit comprising a nozzle 19 and a flat disk gasket 20 positioned between the underside of the nozzle and the bearing surface 14 of the nozzle seat. The nozzle is provided with an inverted L-shaped liquid passageway 21 designed in one position of the nozzle to aline with the opening 15 to provide a liquid conduit from the interior to the exterior of the bottle.

The passageway 21 is of substantially equal cross-section throughout its length and includes a relatively long liquid receiving portion 22, vertically disposed when the bottle is in upstanding position and a relatively short liquid discharging portion 23, normally disposed in horizontal position but which, when the bottle is tipped into pouring position, will extend vertically so as to discharge the stream into the ink-well or other receptacle for receiving the discharged liquid. The nozzle is also provided with a straight, air inlet passageway 24 designed, when the passageway 21 is alined with the

opening 15, to aline with the air inlet opening 16. In this way when the nozzle is in position permitting the discharge of the liquid through the open conduit, an open air intake is provided by the passageway 24 alining with the opening 16.

A substantially flat ring 25 formed of spring metal encircles the lower enlarged body portion 26 of the nozzle and bears on a shoulder 27 formed on the body portion. In order to increase the spring of the ring the inner edge is bent upwardly as shown at 28, in Fig. 1. The ring is provided with a two-part diametrically extending depression, the inner part 29 of which constitutes a stop lug and fits in an arcuate recess 30 formed in one side of the shoulder 27. This construction acts to limit the rotation of the nozzle to and from its open position. The outer part 31 of the ring depression fits snugly within a depression 32 formed in the upper face 33 of the rim 13 and acts to prevent relative rotary movement between the ring and nozzle seat. The nozzle seat, gasket and the outer edge of the spring ring are confined within a retaining ring or ferrule 34, the upper side of which is provided with an inwardly projecting flange 35. The flange laps the spring ring about the same except at the depressed part and coacts therewith to hold the nozzle in rotary position relative to the nozzle seat.

Having thus described my invention, I claim:

1. A closure for a bottle including a spring ring, a ferrule for securing said ring to the bottle, a rotary valvular construction for controlling the flow from the bottle, said construction including a nozzle seat, a pouring nozzle rotatably mounted in said seat and held resiliently in place by said spring ring.

2. A valvular closure for a bottle including a nozzle seat and with an upstanding rim, said rim provided with a locating recess, a nozzle rotatably mounted on said seat, a ring adapted to bear on said nozzle to hold the same in engagement with its seat, said ring provided with a lug depending therefrom and fitted in said recess to prevent relative rotary movement and a ferrule inclosing said valve seat and engaging said ring to secure the same in fixed position relative to the bottle.

3. A valvular closure for a bottle including a nozzle seat and with an upstanding rim, said rim provided with a locating recess, a nozzle rotatably mounted on said seat, a ring adapted to bear on said nozzle to hold the same in engagement with its seat, said ring provided with a lug depending therefrom and fitted in said recess to prevent relative rotary movement, said ring provided with a second lug engaging the nozzle to limit rotary movement thereof and a ferrule

inclosing said valve seat and engaging said ring to secure the same in fixed position relative to the bottle.

4. A valvular closure for a bottle including a nozzle seat having an upstanding rim provided with a locating recess, a nozzle fitted within said rim for rotary movement and provided with a limiting recess, a retaining ring positioned on said rim, provided with means fitted in said recess, to prevent rotary movement, engaging said nozzle to prevent an unseating movement thereof and provided with means engaging in said limiting recess to limit the rotary movement 15 of the nozzle.

5. A valvular closure for a bottle including a nozzle seat, a nozzle mounted for rotary movement relative to said seat, a gasket of compressible material positioned between the nozzle and its seat, resilient means for compressing the gasket between the nozzle and its seat and means for securing the closure to a bottle.

6. A valvular closure for a bottle including a nozzle seat, a nozzle mounted for rotary movement relative to said seat, a gasket of compressible material positioned between the nozzle and its seat, a resilient ring bearing on the nozzle to compress the gasket 30 and means for securing the resilient ring in place.

7. An attachment designed to be affixed to a bottle and including a metallic retaining ring, a valve seat, a valve mounted for rotary movement on said seat, said valve including a base portion rotatably mounted within said ring and held to the seat thereby, and an upper part extending above the ring and means for securing the valve, its seat 40 and retaining ring in position on the bottle.

8. In a device of the class described, the combination of a valve seat, a valve rotatably mounted thereon, a retaining ring pro-

vided with means for locating the same in fixed position relative to the valve seat and 45 operatively engaging the valve to limit its rotary movement.

9. In a device of the class described, the combination of a valve seat, a valve rotatably mounted thereon, a retaining ring provided with means for locating the same in fixed position relative to the valve seat and operatively engaging the valve to limit its rotary movement and bearing on said valve to hold the same in frictional engagement 55 with its seat.

10. In a device of the class described, the combination of a valve seat, a valve rotatably mounted thereon, a retaining ring provided with means for locating the same in fixed position relative to the valve seat and operatively engaging the valve to limit its rotary movement and bearing on said valve to hold the same in frictional engagement 60 with its seat and a metal ferrule for fastening the valve seat and the valve to the bottle, said ferrule provided with means for securing the retaining ring in place.

11. In a device of the class described, the combination of a bottle, a washer positioned thereon, a valve seat positioned on the washer and provided with an upstanding rim, a valve fitted for rotary movement in said seat, a retaining ring positioned on said rim and engaging said valve to force the 75 same toward said seat and a ferrule engaging the outer side of said washer, said rim and said retaining ring to secure the same to the bottle, said ferrule having an inwardly extending flange lapping the outer edge of 80 the retaining ring.

Signed at New York city, in the county of New York and State of New York, this 21st day of August, A. D. 1919.

FRANK H. SILVERTHORNE.
